UNITED STATES PATENT OFFICE.

ALMON B. CALKINS, OF NUTLEY, NEW JERSEY, ASSIGNOR TO AMERICAN MATCH MANUFACTURING COMPANY, OF NEW YORK, N. Y., A CORPORATION OF NEW JERSEY.

MATCH-MAKING MACHINERY.

SPECIFICATION forming part of Letters Patent No. 758,617, dated May 3, 1904.

Application filed June 8, 1903. Serial No. 160,519. (No model.)

To all whom it may concern:

Be it known that I, ALMON B. CALKINS, a citizen of the United States of America, residing at Nutley, county of Essex, State of New Jersey, 5 have invented certain new and useful Improvements in Match-Making Machinery, of which the following is a specification, reference being had to the accompanying drawings, forming a part thereof.

10 My invention relates to match-making machinery, and particularly to apparatus therein for applying paraffin to splints prior to the time they are headed with the match composition.

15 My invention consists in certain novel details of construction and combination of parts to be more fully pointed out hereinafter, and particularly in an improved system for supplying paraffin from a main source of supply 20 to a plurality of paraffin-baths and in separately-controlled heating means for the main and branch portions of the conduit conveying the paraffin from the source of supply to the several tanks.

25 I will now proceed to describe an apparatus embodying my invention and will then point out the novel features in claims.

In the drawings, Figure 1 is a view in central vertical longitudinal section through a 30 portion of a match-making machine, including a paraffin-tank and mechanism for conveying the splints thereover. Fig. 2 is a view in transverse section thereof, the plane of section being taken upon the line 22 of Fig. 1.

35 Fig. 3 is a rear view of a portion of the paraffin-tank, showing particularly the means for raising and lowering the tray therein. Fig. 4 is an enlarged sectional detail view showing a heating system employed for the conduit 40 conveying the paraffin from a source of supply. Fig. 5 is a detail sectional view, on an enlarged scale, through a portion of the paraffin-tank and the tray therein, showing the said tray in its downward or submerged position in full lines and in its raised position in dotted lines.

In the embodiment of my invention herein a tank for holding paraffin is illustrated at 1 in the drawings and is provided with a jacket 2, whereby steam or other heating medium may 50 be applied to keep the paraffin therein in a fluid condition. The tank is supported by a suitable framework comprising legs 33. Splint-carriers 4, holding a number of splints 5, projecting downwardly therefrom, are arranged to travel upon a suitable runway 6 over the said tank. Means for applying a step - by - step movement to the carriers is provided in a cam 7, carried by the main shaft 8, an operating-lever 9, a secondary lever 10 55 in engagement therewith, and an operating-pawl 11, arranged to engage the rigid teeth of suitable drive-racks 12 of the carriers. Continuous rotary movement of the driving-shaft 8 will cause a reciprocation of the levers 9 and 10 and of the operating-pawl 11 to transmit a step-by-step movement to the carriers. A shallow tray 12 is arranged within the tank 1 and is adapted to be submerged within the fluid therein. The tray 12 is provided with a 60 plurality of slides 13, mounted in slideways in the side walls of the tank 1. Such slide and slideway connection permits vertical movement of the tray 12, but prevents any other movement with respect to the said tank. The tray 12 is provided centrally with a plunger 14, which passes through a suitable stuffing-box 15 to the exterior of the tank and is engaged by a yoke or cross-head 16. The yoke or cross-head is connected by means of suitable 65 links or connecting-rods 17 to operating-arms 18, rigidly mounted upon a cross-shaft 19. An arm 20 is also rigidly secured to the shaft 19 and carries the stud or projection 21, which engages the groove of a cam 22, mounted upon 70 a cam-shaft 23. The cam-shaft 23 is driven from the main shaft 8 by suitable gearing 24. At every revolution of the cam-shaft 23 the tray 12 is caused to be raised and lowered from a position within the tank and immersed in 75 the liquid paraffin therein to a position above the level of the tank, as shown in dotted outline in Fig. 5. The completion of the upward movement of the tray 12 is so timed with respect to the step-by-step movement imparted 80 to the carriers that the tray will be in its up-

permost position while the carriers and splints therein are in their rest positions. When moving to its upper position, the tray will carry with it a small quantity of paraffin, 5 which it will at the extreme upper end of its movement apply to the lower ends of the splints in the carriers thereabove. By the time the carriers receive their next forward step-by-step movement the tray will have been 10 lowered out of the way of the splints, so as not to impede their free movement. By this construction and arrangement of parts I am enabled to use a straight runway for the splints and to construct the splint-carriers in the form 15 of sectional frames carrying a number of rows of splints. I am thus enabled to apply the paraffin to a number of splints at the same time, and, further, I am enabled to apply the paraffin to the splints while they are in a rest 20 position.

I supply the tank with paraffin from a suitable source of supply by means of a conduit 26, and I maintain the proper level of the paraffin in the tank by supplying an overflow. 25 This overflow may conveniently be in the form of a groove 25 in the said wall of the tank 1, and a receiver may be arranged beneath the discharge end of the overflow-groove to receive any paraffin which may overflow from 30 the tank. The conduit 26 comprises a set of piping, whereby a number of paraffin-tanks may all be supplied from one source, and for this purpose I provide a main pipe 27 and connect each paraffin-tank therewith by means 35 of individual branch pipes 28, each branch 28 having a horizontal delivery-section 29, in which is arranged a valve 30 to control the supply of material.

As is well known in this art, it is necessary 40 to heat the tanks, reservoirs, and the like which contain the paraffin, together with all the pipe connections, and for this purpose it is usual to either steam-jacket the pipes or vessels or arrange steam heating-pipes therein. In arranging for heating the conduit I have herein shown means for supplying heat to the main pipe 27 by a steam heating-pipe 45 31 therein and have arranged separate and individual heating means for the branch pipes 50 28, as shown in detail in Fig. 4, in order that the main pipe may be heated regardless of whether or not any of the tanks connected thereto are shut off and that the heating means for any of the branch pipes may be 55 conveniently cut off when desired—as, for instance, when the tank connected thereto is not being used. For this purpose I have supplied the branch portions 28 of the conduit 26 each with a steam-inlet pipe 32, arranged to receive 60 its steam from a supply-pipe 33, and with a water-discharge or drip pipe 34, provided at its lower end with a drip-valve 35. The steam-supply pipe 33 has a controlling-valve 36 for controlling the amount of steam 65 supplied. By this arrangement I am enabled

to supply a number of tanks from the main horizontal pipe 27 and maintain a steam circulation therein regardless of how many of the tanks connected thereto are in use at the time. Each tank then being provided with a 70 branch pipe of the conduit similar to 28, separately heated by an individual circulating-pipe controlled by a valve, as 36, the heating of that portion of the conduit connecting with the individual tanks will be only effected 75 while such tanks are in operation, and when such tanks are out of operation the cooling of paraffin in the branch supply will not affect the circulation to other tanks in the system. Further, it will be understood that as 80 paraffin solidifies at atmospheric temperature and requires a heat considerably above atmospheric temperature to become liquid the cooling of the paraffin in any branch will not only not affect the circulation through other 85 parts of the system, but will be a positive advantage, because such solidification will act as a seal and prevent material flowing through such pipes should it become desirable to disconnect the tanks and the paraffin-delivery 90 thereto from the branch supply for purposes of repairs, &c.

It will be understood that I do not desire to be limited only to the precise details of construction and combination of parts as 95 herein shown and described, as they may obviously be varied in wide limits without departing from the spirit and scope of my invention, and it will further be understood that certain portions of my invention may be 100 used with parts of other construction than herein shown.

What I claim is—

1. In match-making machinery, the combination with a paraffin-tank, a tray arranged to be raised and lowered out of and into the paraffin therein, and means for conveying splints over said tank, of a main shaft arranged above the level of the tank, means operated by the said shaft for imparting a step-by-step movement to the splint-conveying means, a cam-shaft 23, gearing 24 connecting the said cam-shaft with the said main shaft, a rock-shaft 19, a lever 20 secured to the rock-shaft and engaging the cam, levers 18 secured to the rock-shaft, links 17 on opposite sides of the tank, connected at their upper ends to the said levers 18, a cross-head 16 below the tank, and to which the lower ends of the said levers are connected, a plunger 14 secured to the cross-head at its 115 lower end, and to the said tray at its upper end, said tank provided at its bottom with an orifice and a stuffing-box for the passage of the said plunger.

2. In match-making machinery, the combination with means for supplying a plurality of tanks with paraffin and means for heating same, of branch pipes leading from said paraffin-supplying means, separate and independent heating means for each of said branch 120 125 130

pipes, and individual controlling means, independent of means for controlling the first said heating means, for the heating means of each of said branch pipes.

5 3. In match-making machinery, the combination with a paraffin-tank, and a supply conduit therefor comprising a main and a branch portion connected together, of separate and unconnected heating means for the main 10 and branch portions of the conduit, said heating means controlled separately and independently of each other, substantially as set forth.

4. In match-making machinery, the combination with a main paraffin-supply conduit 15 27, and a heating-pipe 31 arranged one within the other, of a plurality of independent branch pipes 26 leading from said main conduit, and adapted for connection individually with different paraffin-tanks, a heating-pipe 32 for

each branch pipe 26, and an individual controller 36 for each heating-pipe 32.

5. In match-making machinery, the combination with a main paraffin-supply conduit 27, and heating means therefor, of a plurality of substantially vertical and independent 25 branch pipes 26 leading from said main conduit, and adapted for connection individually with different paraffin-tanks, a heating-pipe 32, closed at the top, arranged within each 30 said branch pipe, an individual controller 36 for each said heating-pipe 32, and a drip-pipe 34 within each said heating-pipe 32, connecting therewith.

ALMON B. CALKINS.
